HENRY C. BUCHWALD, OF BALTIMORE, MARYLAND.

TENDER COAL-LOADING APPARATUS.

1,157,366.

Specification of Letters Patent.

Patented Oct. 19, 1915.

Application filed September 30, 1914. Serial No. 864,193.

To all whom it may concern:

Be it known that I, HENRY C. BUCHWALD, a citizen of the United States, residing at Baltimore, in the State of Maryland, have 5 invented certain new and useful Improvements in Tender Coal-Loading Apparatus, of which the following is a specification.

This invention relates to a tender coal-loading apparatus.

10 The object of the invention is to provide for railroads an improved station for readily coaling the tenders of locomotives.

The invention is illustrated in the accompanying drawing, in which,—

15 Figure 1 is an elevation of the apparatus shown in section on the line 1—1 of Fig. 2; in this figure the coal-dumping car is at the bottom of the pit in the ground. Fig. 2 is a front elevation of the apparatus showing the

20 coal-dumping car in its elevated position, and also showing a section of the pit and the vertical door which closes the chute that leads into the pit. Fig. 3 shows a horizontal plan taken on the cross line 3—3 of Fig. 1.

25 Fig. 4 shows a vertical section of part of the pit, details of the car, and the vertical door, as seen on the line 1—1 of Fig. 2 when the car is down. Fig. 5 is a vertical section of part of the pit, and details on the line 5—5

30 of Fig. 2. Figs. 6 and 7 are side views of part of the coal-dumping car showing the structure of the guide-groove that provides for tilting the car.

35 In carrying out plans for this apparatus a pit is dug in the ground to receive a coal-dumping car which when loaded is to be elevated by suitable means, and which car when at its highest point of elevation is tilted in order to dump its load of coal into 40 a locomotive tender resting on a railroad track on the ground surface.

Referring to the drawing the numeral 8, 45 designates the surface of the ground where the apparatus is located; a rail-road track 9, may be used for any train of cars or only for locomotives and tenders which latter are to be supplied with coal. At one side of the car-track a rectangular-shaped pit 10, is dug 50 into the ground; the depth of this pit may vary but of course will suit the conditions of the locality. A suitable frame-work tower 11, rectangular in horizontal cross-section, projects from this pit into the air, and a coal-dumping car 12, is movable up and 55 down within the tower from the pit to the

top. The frame work of the tower is made of angle-iron. An engine or motor is employed to drive a winding-drum, and a cable connected to the car and said drum is employed to raise and lower the car.

The walls and bottom of the pit have a sheet-metal lining 13; the frame-work 11, of the tower includes standards, cross-bars, braces and plates as shown in the drawing but the particular construction of the tower 60 is unimportant to this invention. The coal-dumping car 12, is rectangular in plan, as seen in Fig. 3, and in moving up and down within the tower this car is guided by two stationary vertical bars 14, which are attached at opposite sides of the tower; these vertical guide bars 14, extend from the pit 10, to a point above the cross-bar 28, near the top of the tower.

Two exterior sides of the car are provided with specially constructed grooved guide blocks 15, 16, that 65 coöperate with the said stationary vertical guide bars 14; the uppermost grooved block 15, is secured rigidly to the exterior side of the car 12, see Figs. 6 and 7; this upper block 70

is stationary and its groove extends in a vertical position when the car-body has its normal horizontal position. A second grooved guide-block 16, is pivotally secured 75 to the exterior side of the car below the said uppermost block 15; this lower grooved block is secured to the side of the car by a screw or bolt 46, placed intermediate the two

ends of the block and serving as a pivot, whereby the car may tilt to dump its load of 80 coal while the lower guide-block 16, remains vertical with its groove engaging the stationary guide bar 14, as in Fig. 6. When the said car is moving up or down, the grooves of the two guide-blocks 15, 16, are in true 85 vertical alinement with each other, as in Fig.

7, and of course during such up-and-down movement the grooves of both blocks will be 90 engaging and sliding along the said guide bar 14. But when the coal-dumping car 12, at time of going up reaches its highest point 95 of elevation, the two uppermost grooved blocks 15, will pass above the top ends 14^a, of the two guide bars 14, and thereby disengage from said guide bars, and at the same 100 time of such disengagement, a stud 17, fixed on each side of the car near its front end and projecting laterally from the car-side, will strike against a laterally-projecting pin 105 18, that is rigidly fixed to the frame-work of 110

the tower 11. Two such stop-pins 18, are used, one being on the tower at a side opposite the other; these two fixed pins on the tower are in the path of the upward movement of the two studs 17, on opposite sides of the car. When the stud-pins on the car at the time of moving upward, strike against the two stop pins 18, on the tower, the front end 19, of the car ceases to move up, but the rear end 12^a, of the car will continue to be raised with the effect of tilting down the front end of the car as in the broken lines in Fig. 1, to cause the coal in the car to slide out.

15 The front end 19, of the car 12, is normally closed by a hinged wall 20, each of whose two ends carry a quadrant-shaped plate 21; this structure serves as a wall and also as a tilting chute to discharge the coal. 20 The wall 20, has hinges 22, that secure it to the car-bottom 23. In Fig. 1, the dumping car 12, is shown in full lines at the bottom of the pit, and the car is also shown in broken lines in tilted position near the top of the 25 tower.

The operation of this dump-car and tilting chute would be as follows: The empty car being at the bottom of the pit, as in Fig. 1, will be loaded with coal passing over the 30 pivoted chute 24; when the car has been filled, the engine 25, would be started and the cables 26, would lift the car. As the car moves upward the top edge of the hinged wall 20, will be pressed outwardly by the 35 coal in the car and said top-edge will slide along in contact with the vertical bar 27, attached to the tower; the upper end of this bar 27, terminates at the cross-bar 28. Just before the stud-pins 17, on the car strike 40 against the stop-pins 18, the hinged wall 20, of the car front will pass above the cross-bar 28, of the tower and said hinged wall with its quadrant plates 21, will then tilt outward through the open spaces in the frame-work 45 of the tower, as indicated by broken lines in Fig. 1; in this outward position the said hinged wall and quadrant plates 21, will serve as a chute to discharge the coal from the car down into the tender 29, shown in 50 Fig. 1. As soon as the coal has been dumped from the elevated car into the tender, the man in charge will reverse the engine and allow the empty car to begin to descend; the hinged wall 20, of the car which 55 has been projecting outward, will be tilted back inwardly to its closed position by the car descending while said hinged wall is dragging back over the said cross-bar 28. As already explained, the car-track 9, on 60 which the locomotives and tenders approach the coal-tower 11, extends along one side of said tower, see Figs. 1 and 3, and the car-tracks 30, on which the loaded hopper cars 31, approach the pit 10, extends along the 65 opposite side of said pit and tower. This

coal-supply track 30, may be elevated by trestle work 32, above the ground surface 8, and thus the track 30, may be higher than the other track 9. Below the trestle 32, is a downward incline 33, leading to the pit 10; 70 a vertically-sliding door 34, slides up and down in a guide-way 35, at the lower end of said incline and at the wall or lining 13, of the pit. A hinged chute 24, takes either one of two positions which are determined 75 by the position of the said vertical door 34. When the sliding door is raised, as in Figs. 2 and 5, it makes a closure between the lower end of the incline 33, and the pit 10, and in this raised position of the door the hinged 80 chute 24, is turned upward toward said incline. When the sliding door 34, is lowered, as in Figs. 1 and 4, the passageway from the incline 33, to the pit is open, and in this lowered position of the door the hinged 85 chute 24, inclines downwardly and its lower end projects into the pit 10. It is to be understood that the vertically-sliding door 34, is raised and lowered by the action of the 90 coal-dumping car in making its up and down movements respectively. When the coal-dumping car 12, is at its downmost position, that is, resting on or near the bottom of the pit, the sliding door 34, will be open and the hinged chute 24, will be in position to deliver coal into said car. When 95 said car 12, is at an elevated position the sliding door 34, will be closed and the hinged chute 24, will be turned upward and be out of its position to deliver coal. 100

The vertically sliding door 34, is provided on its surface adjoining the pit with a block 36, and with a plate spring 37, whose lower end is fastened to the door having its upper end free and normally sprung away from 105 contacting with the door. The door also has at its top edge a projecting bead 38; a plate spring 39, has its lower end made fast to the strip 35, that forms the vertical guideway, and when the said door is raised the top end 110 of this plate spring takes under the bead 38, and serves to retain the door in its raised and closed position. The car 12, at its end adjacent the sliding door 34, is provided with a block 40, which, when the car and door are both down, takes under the head 37, of the plate spring that is fastened to the door. When the car moves upward this block 40, on the car being engaged under the 115 spring-head 37, on the door 34, will have the 120 effect to raise the door. The car end also has a projecting pin 41; this pin may be fastened direct to the end-wall of the car or may be secured into the said block 40, but in either case the pin 41, should project a little farther than the block. This pin 41, serves to engage the block 36, on the vertically-sliding door 34; in the event that the spring-head 37, slips from contact with the block 40, at the 125 time the car moves down, then the pin 41, 130

on the car will engage the block 36, on the door and push said door downward. The car 12, has a flat bottom 23, that may rest on the horizontal bottom 43, of the pit, and said car is provided with a false bottom 42, that is highest at the permanently closed end 12^a, and inclines downward toward the front end 19, of the car wherefrom coal discharges. This inclined bottom 42, facilitates the discharge of coal. The car has at the center of its top edges a grooved roller 44, and at its front end 19, a metal strap 45, with an eye; the lifting cable 26, takes under the said roller 44, and then extends forward horizontally along the top edge of the car-side and is secured to said eye in the strap 45.

Having thus described my invention what I claim is,—

1. In a tender coal-loading apparatus, the combination of a tower provided with two stationary guide-bars attached at opposite sides; a pit in the ground below the bottom of the tower; a downward inclined opening 33, at one side of the tower and leading from the surface to said pit; a vertically sliding door at the lower end of said downward incline; a chute 24, hinged to said incline and adapted to tilt downward when the door is open and project into the pit, and also adapted to turn upward and take position in the space of said incline when the door is closed; and a coal-dumping car movable up and down within the pit and tower and said car

automatically raising and lowering said vertical sliding door by said movements. 35

2. In an apparatus for supplying tenders with coal, the combination of a tower provided with two guide-bars extending vertically from the base to a point above the cross bar 28, near the top of the tower; two laterally projecting pins 18, on the tower at its dumping side; a coal-dumping car vertically movable within the tower and opposite sides of said car provided near its front end with laterally-projecting studs 17, which on the up movement of the car strike against said lateral pins and tilt the car, and said car also provided with a grooved guide-block 15, rigidly secured to the car-side, a second grooved guide-block pivotally secured to the car-sides 50 below said rigidly-secured block, and as the car moves upward the grooves of both upper and lower blocks engaging said side-bars to the top end of the latter where the said uppermost blocks will disengage from the guide bars but leaving the pivoted guide block engaged, thus the car is automatically tilted and its load dumped through the side of the tower while the pivoted block remains engaged with the guide-bar. 55

In testimony whereof I affix my signature in presence of two witnesses.

HENRY C. BUCHWALD.
